UNITED STATES PATENT OFFICE.

PAUL G. DALLWIG, OF CHICAGO, ILLINOIS.

DOLL.

1,413,264.

Specification of Letters Patent. Patented Apr. 18, 1922.

Application filed October 4, 1920. Serial No. 414,496.

To all whom it may concern:

Be it known that I, PAUL G. DALLWIG, a citizen of the United States, residing at Chicago, in the county of Cook and State of Illinois, have invented new and useful Improvements in Dolls, of which the following is a specification.

In my co-pending application Serial No. 262,981, filed November 18th, 1918, I have shown and described a doll's head provided with a plurality of different and interchangeable wigs having releasable connection with the head, so that the doll may be readily changed from one character to another by merely placing on the head the wig having the style of hair-dress of the character desired. The wigs are secured on carrying members or wig tops which are made to complete the top of the head when applied thereto, the head having the upper portion thereof cut away to provide a seat for these wig tops.

The object of the present invention is to provide an improved form of fastening means for releasably connecting each wig top to the head.

In the accompanying drawings:

Fig. 1 is a front view of a doll's head provided with a fastening means of my invention;

Fig. 2 is a vertical sectional view taken on line 2—2 of Fig. 1;

Fig. 3 is a rear view of the head with the wig top removed;

Fig. 4 is a transverse sectional view taken on line 4—4 of Fig. 2; and

Fig. 5 is a perspective view of the fastening member.

In the drawings, 1 indicates a doll's head made hollow and of metal, such as aluminum, so that the head will be unbreakable and light in weight. The head has a neck portion 2 to be secured to the body of the doll. The head is cut away above the ears and eyes to provide a substantially flat seating surface 3 for a removable top or crown portion 4 having a shape and size to complete the top of the head when applied thereto, as shown in Figs. 1 and 2. The crown or top portion 4, as shown, is solid and has its outer surface smooth, and curved to conform to the top of the doll's head. On this surface is a wig 5. As set forth in my said co-pending application, each head is provided with a plurality of these wig tops 4, the set of wig tops for the head hav-

ing thereon wigs with different styles of hair-dress, so that the doll may be readily and easily changed from one character to another by merely placing on the head a wig top having the character of wig desired.

To releasably connect the wig top to the head, I provide means constructed as follows. The head has a plug 6 projecting above the same and supported by arms 7, 7 extending across the open top of the head. These arms are cast integral with the plug and the wall of the head, and the plug extends upward substantially at right-angles to the plane of the seating surface 3. The plug 6 is centrally arranged, or substantially so, and enters a socket 8 formed in the wig top 4 and opening outward through the flat under surface thereof.

Co-operating with the plug 6 is a fastening member 9 made of sheet metal and having the form shown in Fig. 5. This member 9 has end flanges 10, 11 at right-angles to the intermediate portion and extending on opposite sides thereof. The mid portion comprises side strips 12, 12, between which is a resilient latch member 13 integral at one end with the flange 10 and free at the other end. The member 9 is inserted into the socket 8 with the end flange 10 secured by screws 14 against the flat under surface of the wig top, as shown in Fig. 2. The other end flange 11 is at the inner end of the socket, and the latch member 13 projects into the socket to engage the plug 6 and have its projection 15 snap into a notch 16 in the plug 6 adjacent its outer end. The notch 16 extends across the plug, as shown in Fig. 3. The side of the plug 6 provided with the notch fits against the member 9 and is substantially flat, while the remaining portion of the plug is curved, thus making the plug substantially D-shaped in transverse cross-section. This together with the plug fitting against the mid-portion of the member 9 holds the wig top and head from rotating or turning with respect to each other when these parts are connected together by the latch member 13. Moreover, the plug and socket having such shape, prevents placing the wig top on the head in any but the proper position, and thus guides the wig top on the head.

By the construction shown and described, the wig top will become connected to the head when applied thereto, the co-operating

fastening elements engaging in placing the wig top on the head, and these in effect act automatically. The fastening element 13 on the wig top is protected from injury by being located in the socket 8, and thus does not project outside of the wig top and consequently will not be broken off, bent or otherwise displaced or damaged when the wig top is off of the head and lying in a box or 10 drawer or other place when not in use.

The plug 6 being at right-angles to the seating surface 3 and to the flat under surface of the wig top allows the wig top to be removed from the head by merely pulling 15 the same upward. When on the head, the connection between the head and the wig top, not only allows for ready and easy disconnection and separation thereof, but provides a connection which positively holds 20 the wig top on the head and prevents the wig top from dropping or being thrown off the head accidentally.

The exact details of construction shown and described may be variously changed 25 and modified without departing from the spirit and scope of my invention.

I claim as my invention:

1. A doll's head made in two separable parts, one of said parts forming the crown 30 or top portion of said head, means for guiding the crown or top portion on the remaining part of said head, comprising a plug on one of said parts for entering a socket in the other of said parts, and coacting means carried by said respective parts and located 35 within the outer margins thereof for releasably fastening the two together.

2. A doll's head made in two separable parts, one of said parts forming the crown 40 or top portion of said head, means for guiding the crown or top part on the remaining part of said head, comprising a plug on one of said parts for entering a socket in the other of said parts, and coacting fastening 45 members associated with the plug and socket, respectively, for releasably securing said crown or top part to the head part.

3. A doll's head made in two separable parts, one of said parts forming the crown 50 or top portion of said head, means for guiding said crown or top part on the remaining part of said head, comprising a plug on one of said parts for entering a socket in the other of said parts, and a resilient latch 55 secured in said socket to releasably engage said plug.

4. A doll's head, having the upper portion thereof cut away to provide a substantially

flat seating surface, a top or crown portion adapted to seat on said surface and complete 60 the top of the head, a plug secured to and projecting upward from the top of said head and having a notch at one side thereof, said crown portion having a socket opening through the lower surface thereof and adapted 65 to receive said plug, and a resilient latch member located in said socket and secured to said top or crown portion and adapted to engage said notch when the top or crown portion is placed on said head.

5. A doll's head having the upper portion thereof cut away to provide a substantially flat seating surface, a top or crown portion adapted to seat on said surface and complete 75 the top of the head, a plug secured to and projecting upward from the top of said head and having a notch at one side thereof, said crown portion having a socket opening through the lower surface thereof and adapted to receive said plug, and a clip having a 80 latch member and an end flange, the latter secured to said top or crown portion against the under surface thereof and the former extending into said socket to engage the notch in said plug.

6. A doll's head having the upper portion thereof cut away to provide a substantially flat seating surface, a crown or top portion adapted to seat on said surface and complete 90 the top of the head, a plug secured to and projecting above the top of said head and having one side substantially flat with a notch therein, said crown or top portion having a socket opening into the under surface thereof to receive said plug, and a clip 95 having an end flange and a flat portion provided with a resilient latch member, the end flange being secured to the under surface of the crown or top portion with the flat portion and latch extending into the socket to 100 fit against the flat side of the socket and engage the notch in said plug.

7. A crown or top portion for a doll's head, comprising a body portion having the upper surface thereof substantially smooth 105 and curved to conform to the curvature of the top surface of a doll's head, said body portion being provided with a plug-receiving socket opening through the under surface of said body portion, and a resilient 110 latch member in said socket and secured to said body portion.

In testimony that I claim the foregoing as my invention, I affix my signature, this 28th day of September, A. D. 1920.

PAUL G. DALLWIG.
